UNITED STATES PATENT OFFICE

162,884

AUTOMOBILE

Adolph Ronning, Minneapolis, Minn.

Application April 22, 1948, Serial No. 145,898

Term of patent 14 years

(Cl. D14—3)

To all whom it may concern:

Be it known that I, Adolph Ronning, a citizen of the United States, residing at Minneapolis, in the county of Hennepin and State of Minnesota, have invented a new, original, and ornamental Design for Automobile, of which the following is a specification, reference being had to the accompanying drawings, forming part thereof.

Fig. 1 is a side view of an automobile, showing my design.

Fig. 2 is a top plan view of the automobile.

Fig. 3 is a front end view of the automobile.

Fig. 4 is a rear end view of the automobile.

Fig. 5 is a front and side perspective view of the automobile.

I claim:

The ornamental design for an automobile, as shown.

ADOLPH RONNING.
